AIR HEATING AND CONDITIONING
APPARATUS

Charles H. Wagner, Camden, N. J.

Application July 2, 1937, Serial No. 151,627

13 Claims. (CL. 236—44)

The ordinary fuel used in a household heater contains a large percentage of hydro-carbons, which when oxidized by combustion, will produce a large amount of water vapor. For example, in the average house burning 476 cu. ft. of 500 B. t. u. gas per hour, there will be produced about 85 gallons of moisture in 24 hours. Since it requires only about 6 to 7 gallons of water per 24 hours to maintain a relative humidity of 40% at 72° F. in any ordinary house, it is seen that there is an ample supply of available moisture that can be used for properly humidifying said house.

One object of the present invention is to provide a process and apparatus for utilizing the water vapor naturally present in the gases of combustion of gases burned in a heating unit, for air conditioning a room.

The invention is applicable for use where the gaseous fuel being burned contains a relatively large percentage of free or combined hydrogen and producing a relatively large percentage of moisture in the combustion gases. It is not applicable where coal or oil is used as the fuel and where the percentage of moisture is low and there is liability of odors or carbon monoxide gas resulting from incomplete combustion.

For carrying out this object, the temperature of the combustion gases is lowered below the dew point so as to condense a portion of the moisture. A controlled amount of the gases saturated with moisture is then introduced into the room to be humidified.

Another object is to provide a process and apparatus for removing objectionable or dangerous ingredients from the combustion gases before said gases are injected into a room for air conditioning purposes.

This object is achieved by the washing and scrubbing action of the dropping particles of condensed water vapors in the gases of combustion.

Another object is to provide a process and apparatus, which utilizes the waste heat from the gases of combustion by heating a supply of air to be injected into a room, and which at the same time lowers the temperature of said gases to bring the vapor contents nearer the dew point and thereby facilitating the use of the moisture for air humidifying purposes.

Another object of the present invention is to provide a combined heating and air conditioning unit of the type referred to, which is operated automatically in its entirety.

Various other objects, features and advantages of the present inventions will be apparent from the following particular description, and from an

inspection of the accompanying drawing in which the single figure shows an apparatus, somewhat diagrammatic and partly in section embodying the present invention for the purpose of illustration, and adapted for carrying out the process of the present invention.

In carrying out the process of the present invention, the temperature of the flue or combustion gases from a heater is lowered sufficiently to saturate said gases for room humidifying purposes and at the same time to effect condensation of a good part of its water vapor content. The condensed water in dropping across the path of movement of the gases, washes and scrubs said gases of its objectionable ingredients including soot, and dust, and renders said gases suitable for air conditioning purposes. The lowering of the temperature of the flue gases is effected by passing said gases in heat exchange relationship with fresh air, the resultant heated fresh air being injected into the room to supplement the direct heating from the heater unit.

The apparatus shown in the accompanying drawing comprises an ordinary furnace 10, which may be of any suitable construction, but which is advantageously of the steam or hot water type having an oil or gas burner. This furnace is shown mounted in the cellar of an ordinary home below the ground floor 11, and has the conventional steam or hot water piping system 12 leading to a series of radiators 13 disposed respectively in rooms A.

The combustion gases from the furnace 10 are delivered from the upper end of said furnace, through a flue or pipe 16 leading into the bottom of an insulated heat exchanger 17, which includes a series of staggered horizontal tubes 18, advantageously provided with the usual radial fins 19 for increasing their heat exchange surfaces. The tubes 18 are expanded at their ends into header plates 20 spaced from the side walls 21 and 22 of said heat exchanger to form an inlet chamber 23 and an outlet chamber 24 on opposite ends of said series of tubes. The wall 22 may be hinged to form a clean-out door, and is fitted with a heavy glass pane whereby the condition of the chamber 24 may be inspected from the outside thereof. Connected to the bottom of this chamber 24 is a drain pipe 24a through which flows the condensed moisture with such impurities of the gas mixture as may be in solution or suspension, and which have been scrubbed from the flue gases by the descending droplets of condensed moisture.

Disposed below the tubes 18 is a removable

and cleanable filtering bed 27, preferably made of mineral wool and open at its lower side to the atmosphere to permit admission of outside air through said bed and around the tubes 18. This air is barred from intermixture with the flue gases in the heat exchanger 17 by the header plates 20, which isolate the two chambers 23 and 24 from said air.

Disposed at the upper end of the heat exchanger unit 17, is a cupola 25, provided at its upper end with branch ducts 26, which extend vertically through the floor 11 and if desired through room walls 28, to the usual type of hot air registers.

15 In order to draw air into the heat exchanger unit 17 through the filter bed 27, there is provided in the cupola 25 a pair of centrifugal fans 30, mounted on a common shaft 31, driven by a suitable motor 32 disposed outside of said unit.

20 Connected to the bottom of the chamber 24 of the heat exchanger 17, is a conduit 35 leading to the inlet of an induced draft fan 36, which is driven from a suitable motor 37 and which has an outlet connected to a duct 38, branching at its

25 upper end into a conduit 40 leading into a chimney 41, and a conduit 42 leading into the heat exchanger 17 above the series of tubes 18. The branch conduit 40 has a check valve 44 opening towards the chimney 41, and the branch conduit

30 42 has a damper 45 automatically controlled from a motor or solenoid 46 controlled in a manner to be hereinafter described.

As is common in many types of gas furnaces the flue pipe 16 may be provided with a series of circumferential slots 50 encircled by a bell 51 connected to said pipe. These slots 50 may be provided either on the outside of the furnace 10 or in the inside of the casing of the furnace, as shown in the drawing, and the portion of the furnace 40 wall opposite these slots may have an opening 52 covered with a grille 53. The draft induced by the blower may thus draw in air to dilute, cool and reduce the absolute humidity of the resulting air and flue gas mixture.

45 The pipe 16 during normal operations is under a slight vacuum due to the induced or forced draft in the system, so that air is admitted through the slots 50 and into the pipe 16, and is carried with the flue gases into the heat exchanger 17.

The temperature in the rooms is controlled by a thermostat 60 in one of said rooms, and the humidity is controlled by a hygrostat 61, these control members being connected by conductors 62 to 55 a relay unit 63 in a well known manner.

The relay unit 63 has a pair of conductors 66 leading to the burner valve, fuel pump or other fuel supply means for the furnace 10, conductors 67 leading to a reverse acting thermostat 64, conductors 68 leading to the motor 32, conductors 69 leading to the motor or solenoid 46, and conductors 70 leading to the fan motor 37.

65 All of the temperature and humidity control means per se form no part of the present invention, and may be of any well known constructions.

When the temperature in the rooms is sufficiently high the thermostat 60 will close circuits through the relay to shut off the burner through the conductors 66 and stop the fan 36. When the 70 temperature in the interchanger has dropped below a given limit, a thermostat bulb 65 in the cupola 25 acts through a circuit closer 64 and the relay 63 to stop the fans 30.

In the operation of the apparatus, when the 75 temperature of the rooms is below the setting of

the thermostat 60, the furnace 10 and the fan 36 are simultaneously started through the thermostatic control means described. The operation of the fan 36 creates a slight vacuum in the pipe 16, so that air is induced through the slots 50 into said pipe. The damper 45 is closed, and the flue gases in passing through the duct 40 open the swinging check valve 44. Any back draft during this operation is prevented as a result of the pressure produced by the fan 36.

10 The mixture of flue gases and fresh air is introduced into the chamber 23 of the heat exchanger 17, passes at a comparatively low speed through the tubes 18 into the chamber 24, and is forced by the fan 36 through the duct 40 and into 15 the chimney 41. When the temperature in the heat exchanger 17 is below the setting of the thermostat 64, the fans 30 are started in operation through the thermostat control means described, to draw air through the filtering bed 27, 20 and around the tubes 18, thereby causing this air to be heated by the warm mixture of flue gases and air passing through said tubes. The heated fresh air is delivered through the branch ducts 25 26 into the rooms to supplement the heating of the radiator units 13 and at the same time create slight positive pressure in the heated areas to prevent draft into the room through windows and doors and to provide ventilation. The drawing of 30 comparatively cool air through the heat exchanger 17 and around the tubes 18 causes the temperature of the mixture of flue gases and air to be lowered, so that when this mixture reaches the chamber 24 the temperature thereof will be 35 below its dew point. The lowering of the temperature of this mixture of flue gases and air, causes a condensation of a substantial portion of its water vapor, and as the particles of condensed water drop they wash and scrub the flue gases and remove the ordinarily objectionable ingredients of said gases, including soot and dust. The provision of a glass in the door 22 serves not only to permit inspection of the interior of the chamber 24 from the outside so that the necessity of 40 cleaning out said chamber may become easily apparent by such inspection, but also serves as a condensing service to further remove excess moisture from the mixture.

While the humidity in the rooms is maintained at the level of the setting of the hygrostat 61, 50 the damper 45 will be in closed position to block the passage of the saturated flue gases and air mixture into the upper end of the heat exchanger 17. However, as soon as the humidity reaches below a predetermined value as determined by the setting of the hygrostat 61, the operation of the motor 46 is initiated to rotate the damper 45 into open position, thereby permitting the saturated mixture of flue gases and air to be delivered into the upper end of the heat exchanger 17 and to be intermixed with the heated fresh air which has been drawn through the filtering bed 27. Enough of this saturated air is introduced into the room through the branch ducts 26 to raise the humidity of the rooms to the setting of the hygrostat 61. 55 As soon as this condition has been achieved the motor 46 is automatically operated to close the valve.

When the rooms have reached the temperature 70 setting of the thermostat 60, the furnace 10 and the draft fan 36 will be shut down. The fans 30 however will continue to operate until the temperature in the upper end of the heat exchanger 17 is lowered to the setting of the thermostat 64.

75 It is seen that by means of the present inven-

tion, there is provided an economical process and apparatus, operated entirely automatically for heating and humidifying a room. Also by means of the present construction, any particular area 5 or part of a building such as a solarium, can be heated above the central point determined by the thermostat 60, by a proper setting of the thermostat 64.

Having thus described my invention what I 10 claim as new and desire to secure by Letters Patent is:

1. The process of heating and humidifying a room, which includes the steps of introducing air into the flue gases from a gas furnace, passing 15 the mixture of flue gases and air into heat exchange relationship with a separate body of air to raise the temperature of said body of air, and to lower the temperature of said mixture sufficiently to cause condensation of a substantial 20 portion of the water vapors in said mixture, whereby said mixture is washed and scrubbed of its objectionable ingredients, and injecting the resultant heated body of air and a small portion of the saturated mixture into said room in 25 controlled relative proportions.

2. A combined heating and air conditioning unit comprising a gas furnace, means for lowering the temperature of the flue gases from said furnace below their dew point, and means for injecting a small portion of the resultant saturated 30 flue gases into a room to be air conditioned.

3. A combined heating and air conditioning unit for a room comprising a gas furnace, a radiator in said room, a piping system between 35 said furnace and said radiator for delivering heating fluid to said radiator, a heat exchanger, a flue pipe connection between said furnace and said heat exchanger, means for drawing air into said heat exchanger in heat exchange relationship with the flue gases delivered thereto, and in sufficient amounts to lower the temperature of 40 said flue gases below their dew point, and means for injecting a small portion of the resultant saturated flue gases into said room.

4. A combined heating and air conditioning unit comprising a gas furnace, a heat exchanger having a series of substantially parallel tubes, and a pair of chambers disposed on opposite ends of said tubes, and communicating with the interior of said tubes, a flue pipe connection between said furnace and one of said chambers, a passageway between the other chamber and a room to be humidified, means for drawing air into said heat exchanger and around said tubes 55 in sufficient amounts to lower the temperature of said flue gases below their dew point, means for delivering a portion of said flue gas to the outside atmosphere and a portion of said passageway, and a humidostat in said room to control 60 the amount of said last mentioned portion.

5. A combined heating and air conditioning unit comprising a gas furnace, a heat exchanger, a flue pipe connection between said furnace and said exchanger for introducing flue gases into 65 said exchanger, said exchanger having an inlet through which air is drawn therein, a fan in said exchanger for drawing air through said inlet in heat exchange relationship with said flue gases, and in sufficient amounts to lower the temperature 70 of said flue gases below their dew point, a filtering bed across said inlet for filtering the air drawn into said exchanger, and means for delivering a part of the saturated flue gases from said heat exchanger into a room to be humidified.

75 6. A combined heating and air conditioning

unit comprising a gas furnace, a heat exchanger, for lowering the temperature of the flue gases from said furnace below their dew point, a passageway between the outlet of said exchanger and a room to be humidified, for delivering the saturated flue gases into said room, a valve in 5 said passageway, and means automatically responsive to the humidity condition in said room for operating said valve.

7. A combined heating and air conditioning unit for a room, comprising a gas furnace, a heat exchanger, a flue pipe connection between said furnace and said heat exchanger, means for drawing air through said heat exchanger in heat exchange relationship with the flue gases, and in sufficient amounts to lower the temperature of said flue gases below their dew point, a passageway for delivering the resultant saturated flue gases from said heat exchanger, said passageway having two branch ducts, one leading 10 to a chimney and the other leading to the heated air emerging from said heat exchanger, a pipe connection between said heat exchanger and said room for delivering the mixture of saturated flue gases and heated air into said room, a valve in 15 said last mentioned duct, and means automatically responsive to the humidity condition in 20 said room for controlling the operation of said valve.

8. A combined heating and air conditioning unit for a room, comprising a gas furnace, a flue pipe connected with said furnace and having a branch leading to the outside atmosphere and a branch leading to said room, a damper in said last mentioned branch and a humidostat in said room for controlling said damper and thereby controlling the amount of moisture laden flue 25 gas delivered to the room in accordance with the relative humidity of the air in the room.

9. The process of heating and humidifying the air of a room, which includes burning a gaseous fuel, utilizing the resulting heat to raise the temperature of the room, introducing the air into the flue gases to heat the air and lower the temperature of the flue gases, cooling the mixture of the flue gases and air below their dew point to condense a portion of the moisture, removing from the gas mixture the condensed moisture and any constituents of the gas mixture dissolved and suspended in the condensed moisture, delivering a portion of the resulting purified moisture-saturated gas mixture into said room, and controlling the volume of said portion in accordance with the humidity of the air in the room.

10. The process of heating and humidifying the air of a room, which includes burning a gaseous fuel, introducing air into the flue gases to heat the air and lower the temperature of the flue gases, passing the mixture in heat exchange relationship with the current of air to cool said mixture below the dew point to condense a portion of the moisture and thereby effect washing and scrubbing of the flue gases, removing from the gas mixture the condensed moisture and any constituents of the gas mixture dissolved and suspended in the condensed moisture, delivering the heated current of air to the room to heat the latter, delivering a portion of the resulting purified moisture-saturated gas mixture into said room, and controlling the volume of said portion in accordance with the humidity of the air in the room.

11. The process of heating and humidifying the air of a room, which includes burning a gaseous

fuel, passing the flue gases into heat exchange relationship with a current of air to cool said flue gases below their dew point to condense a portion of the moisture and thereby effect washing 5 and scrubbing of the flue gases, removing from the flue gases the condensed moisture and any constituent of the gas mixture dissolved and suspended in the condensed moisture, and delivering the said air current and a portion only of the 10 resulting purified moisture-saturated flue gases into said room.

12. The process of humidifying a room, which includes the steps of burning a gaseous fuel, lowering the temperature of the flue gases below 15 their dew point to thereby condense moisture from the flue gases and remove constituents of the flue gases, separating the condensate from the purified moisture-saturated flue gases, and delivering a portion of said purified flue gases to 20 the room to humidify the latter.

13. A combined heating and air conditioning unit for a room comprising a gas furnace, a heat exchanger, a flue pipe connection between said furnace and said heat exchanger, means for drawing air through said heat exchanger in heat exchange relationship with the flue gases and in sufficient amount to lower the temperature of said flue gases below their dew point and thereby condense moisture from said flue gases, said heat exchanger having an outlet for the condensed 10 moisture and any constituents of the flue gases dissolved or suspended therein, means for injecting a small portion of the resulting saturated purified flue gases into said room, means for delivering the air from said heat exchanger to 15 said room, and means for controlling the amount of the flue gases delivered to said room in accordance with the humidity conditions in said room.

CHARLES H. WAGNER. 20
